UNITED STATES PATENT OFFICE.

BERT SELBY, OF INDIANAPOLIS, INDIANA.

MEANS FOR APPLYING PASTE OR THE LIKE TO PAPER.

1,358,026.

Specification of Letters Patent.

Patented Nov. 9, 1920.

Application filed August 30, 1919. Serial No. 320,885.

To all whom it may concern:

Be it known that I, BERT SELBY, a citizen of the United States, and a resident of Indianapolis, county of Marion, and State of Indiana, have invented a certain new and useful Means for Applying Paste or the like to Paper; and I do hereby declare that the following is a full, clear, and exact description thereof, reference being had to the accompanying drawings, in which like numerals refer to like parts.

This invention relates to a paste applying device for applying paste or like substances to paper, and in this case more specifically to wall paper, reference being had to my former application, Serial No. 276,230.

The main object of the invention is to provide a portable, mechanical means for quickly and rapidly applying paste to wall paper, in place of the old method used in common practice in applying paste with a brush.

The chief feature of this invention is the simplicity of its construction, doing away with any complicated mechanism and gears, and simplifying the construction to a point where it is practical as a commercial article and for production.

For obtaining these objects, the device comprises a paste containing receptacle in combination with which is a device for applying paste by simply pulling the paper therethrough, and also means for trimming the edges of the paper longitudinally as it is pulled through the paste applying device and for stripping the paper when the occasion arises, all of which is for the purpose of saving much time and energy, which is lost ordinarily in the common practice of applying paste with a brush, heating the paste and cutting the paper, independently of each other. It should also be observed that it has the advantage of being removable and portable so as to be carried from one job to another and quickly and easily installed. It is also operated by hand, doing away with all unnecessary mechanism and complexity and being entirely operated by simply drawing the paper through the device.

In the drawings, which are made a part of this application, Figure 1 is a side elevation of the device mounted upon a table. Fig. 2 is a plan view looking down upon the device, as shown in Fig. 1. Fig. 3 is an enlarged section taken on the line 3—3 of

Fig. 2. Fig. 4 is a side elevation showing the adjustment for the paste applying roller. Fig. 5 is an enlarged plan view taken on the line 5—5 of Fig. 1 showing the arrangement of the mounting for the paper roll. Fig. 6 is a front elevation of the trimming mechanism.

In the drawings there is shown a table 10 upon which wall paper is pasted, cut and folded, having legs 11 for supporting the same. Secured at one end of said table there is a bracket 12 braced by a brace 13, on which is secured a sheet metal housing member 14. Removably and adjustably contained in said housing member, there is a paste containing receptacle 15 which is adapted to set within water, as shown at 16, which is heated by means not shown herein for keeping the paste at the proper temperature during the operation of the applying mechanism.

Adjustably mounted within the paste containing receptacle 15 there is a paste applying roller 17 mounted on the bracket 18 which extends over the edge of the housing, and is adjustably secured thereon by the thumb screw 19. The paste applying roller is adjusted so that its peripheral surface barely extends into the paste 20 contained in the receptacle 15. Mounted immediately above the paste applying roller, and adjacent thereto, there is a paper carrying cylinder 21 having its bearings mounted in the ends of the arms 22, which are rigidly secured upon the rod 23, said rod being mounted in the end brackets 24 and extending longitudinally of the housing for the full length thereof. The cylinder 21 rests upon the roller 17 by gravity, being held in proper relation thereto by the arms 22 and spaced therefrom a small fraction of an inch by means of thin metal strips 25 surrounding the periphery of the roller 17 at each end thereof, said strips being of narrow width. Loosely mounted upon the rod 23 there are supporting arms 26 on which is mounted a longitudinally extending brush 27, said brush being in position to engage the paper 28 adjacent the cylinder 21 for removing any excess paste and smoothing and spreading it over the surface thereof. The brush 27 rests on the paste by its own weight.

The paper roll 29 is mounted between the disks 30 and 31, said disks being adjustably mounted upon the shaft 32, which is gradu-

ated to indicate the position of the disks for a given width of paper. The shaft 32 is mounted at each end in the bearings 33 and 34, the bearing 34 being mounted upon the 5 pin 35 extending through the bracket 36 and maintained yieldingly in contact with the shaft 32 by the spring 37, whereby the pin 35 may be pulled outwardly and the shaft 32 removed from its bearings. Upon the 10 removal of the shaft, the disk 30 is taken off and the paper roll mounted thereon in operative position. The brush 27 is then thrown back out of engagement with the cylinder 21, and the cylinder 21 is elevated 15 out of engagement with the roll 17, so that the paper may be placed about said cylinder, after which it is dropped back into contact with the roll 17 and the brush placed in contact therewith, after which the device is 20 ready for operation.

For trimming the edges of the wall paper, there are trimming disks 38 and 39 mounted near each end of the shaft 40, said shaft being driven by a gear 41 in position to mesh 25 with the driving pinion 42, which is driven by the gear 43, mounted upon the pin 44 extending from the end of the cylinder 21. Adjustably mounted on the shaft 40, by means of the set screw 45, there is a gear 46 30 which is integral with the collars 47 and 48, which are connected by the bushing 49, the trimming disks 38 being secured to the collar 48 so that as the shaft 40 is rotated, the gear 46 and the trimming disks 38 would be 35 rotated and the gear 50 driven so as to drive the disk 39. The spindle upon which the gear 50 and the disk 39 are mounted is supported in the bracket 51 surrounding the bushing 49 and is provided with a downwardly projecting indicating finger 52 which extends to within close proximity of the paper 28 as it passes over the roller 53. The bracket 51 also supports a table 54 having a slot therein and through which the cutting 40 disks extend, upon which the paper rides as it is drawn through the machine. By means of this arrangement, the paper is accurately 45 trimmed and the indicating finger 52 will show the operator the exact line upon which 50 the paper will be cut, so that he can trim the paper in accordance with the figures shown thereon.

For cutting the paper into strips there is provided cutting disks 55 and 56 mounted 55 upon the shaft 57, which is carried by the arm 58 having its other end pivoted on the rod 23 so that when it is desired to strip the paper, the arm 58 may be thrown over into such a position that the disks 55 and 56 will 60 engage the top of the cylinder 21 through the paper carried thereon and be yieldingly held in cutting position by spring tension which is not shown herein as this feature forms no part of the invention.

65 The paste containing receptacle 15 is ad-

justably supported in the housing 14 by means of the lever 59 which is fulcrumed at 60 on the bracket 24, having one end connected thereto by the link 61 and the other end pivoted to the rod 62, which is provided 70 with ratchet teeth in its lower end to engage the member 63 secured to the lower part of the housing. This will enable the containing receptacle to be adjusted in elevation according to the level of the paste so that the 75 roller 17 may at all times be immersed therein.

The invention claimed is:

1. A paste applying mechanism, including a paste containing receptacle, a paste applying roller mounted so as to engage the paste in said receptacle, a paper carrying cylinder mounted adjacent to said paste applying roller in engagement therewith about which the paper may be drawn so as 85 to engage and drive said roller, whereby a coating of paste will be applied thereto, and means for spacing said roller and cylinder apart so as to permit the paste to remain upon the surface of the paper as it passes 90 therethrough.

2. A paste applying mechanism, including a housing member, a paste containing receptacle supported in said housing member, a paste applying roller adjustably 95 mounted in said housing, a paper carrying cylinder removably mounted adjacent to said roller, and a lever pivoted to said receptacle having one end linked to said receptacle and the other end pivoted to an adjusting 10 bar for adjustably supporting said receptacle within said housing.

3. A paste applying mechanism, including a housing member, a paste applying roller adjustably mounted in said housing, 10 means for supplying paste to said roller, a paper carrying cylinder mounted on arms pivoted to said housing, whereby said cylinder will lie adjacent and in contact with said roller and be removable therefrom by 11 the elevation of said arms, and a stationary brush extending longitudinally of and in engagement with said cylinder, said brush being held in position by pivotally mounted arms for permitting it to be drawn out 1: of engagement with said cylinder so that the paper may be inserted between said roller and cylinder.

4. A paste applying mechanism, including a paste supplying member and a paper carrying cylinder mounted adjacent each other, means for supplying paste to said cylinder for applying it to the paper, a plurality of trimming disks adjustably mounted thereon so as to be slidable longitudinally of said mechanism, and indicating means on said trimming disks adapted to indicate the line of cutting upon the paper as it is pulled through said mechanism.

5. A paste applying mechanism includ- 1

ing a paste applying member and a paper carrying cylinder mounted adjacent each other, means for supplying paste to said cylinder for applying it to the paper, a plurality of trimming disks adjustably mounted thereon so as to be slidable longitudinally of said mechanism and downwardly

projecting indicating fingers mounted in connection with said disks and extending in close proximity to the paper for indicating 10 the line of cutting thereon.

In witness whereof I have hereunto affixed my signature.

BERT SELBY.
